C. P. LADD.
PLATFORM BALANCE.

Patented May 17, 1836.

Calvin P. Ladd of Stasburgh. Vermont.

Letters Patent.

The schedule referred to in these Letters Patent and making part of the same containing a description in the words of the said Calvin P. Ladd himself of his improvement in the platform Balance.

Be it known that I, Calvin P. Ladd of Stasburgh in the county of Benning and state of Vermont, have made a new and useful improvement in the useful art, being a machine for weighing, called "Ladd's Improved Platform Balance," which is described as follows reference being had to the annexed drawings of the same, making part of this specification.

This Balance consists of a rectangular frame A. of any convenient size and strength adapted to the purpose intended. On the top and bottom of this frame are cast iron plates B. & C. embracing the frame A. and secured to the same by screws. On the upper cast iron plates B. are left or drilled apertures to admit thesmithy D. to which are suspended the loops E. made of an oval figure. In these loops are suspended the levers F. G. & H. by pins I projecting from the side of the levers. These levers are connected together and suspended by rings K. and pivots L. which have heads or projections to prevent the rings from slipping off. The platform upon which the weight to be weighed is placed rests upon four pivots M. projecting from the inner side of the levers; the bearings on the under side of the platform, and which rest upon the pins M. are faced with steel. Four rods N. to keep the platform in its proper position and prevent its touching the sides of the frame, extended from the sides of the platform to the centre of the frame, where they are attached to pins or points O. which will prevent the platform from vibrating horizontally in any direction. The levers F. are brought together at P. where there is a moveable pivot Q. for adjusting the levers; this pivot is attached by screws and nuts which may be adjusted by moving the bolts backward or forward, in oblong mortises in the ends of the levers as required. This pivot is suspended in a hook formed at the end of a vertical

rod C. extending to the Stockyard S. hanging in the usual manner. At the end of the long arm of the Stockyard is suspended a box T. containing weight for balancing the platform. At the short arm of the Stockyard is an adjusting weight and spring R. for balancing the platform to the utmost nicely.

The long arm of the Stockyard or lever is graduated to balance any required weight in pounds &c. The short arm is graduated for determining the amount.

Operation. The platform is first brought to an equilibrium by the weighted box-ball and spring; the article to be weighed is then placed upon the platform, which is suspended to the short end of the lever or Stockyard, by a combination of levers of the second order, — the point is then moved on the long arm of the lever from the fulcrum towards the small end, which will indicate the weight in pounds. the answer being shown by the small pin on the short-end of the lever which is moved towards the fulcrum.

What I claim as my invention and which I desire to secure by Letters Patent, consists in the before described Balance for weighing weights.
